UNITED STATES PATENT OFFICE

149,549

DESIGN FOR A SLIPPER

Joseph Goldstein, Brookline, Mass.

Application November 1, 1947, Serial No. 142,260

Term of patent 14 years

(Cl. D7—7)

To all whom it may concern:

Be it known that I, Joseph Goldstein, a citizen of the United States of America, residing at Brookline, in the county of Norfolk and State of Massachusetts, have invented a new, original, and ornamental Design for Slippers, of which the following is a specification, reference being had to the accompanying drawing, forming a part thereof, in which:

Figure 1 is a plan view, and

Figure 2 is a side elevational view of a slipper, showing my new design.

The dominant feature of the design is the combination of a two piece vamp, each piece of a different color or shade appearance, with the pieces joined diagonally across the vamp.

I claim:

The ornamental design for a slipper, as shown and described.

JOSEPH GOLDSTEIN.
